(57) **CLAIM**

I claim the ornamental design for the garden weeder, as shown and described.

DESCRIPTION

The present design relates to garden weeding hand tool having a gripped handle in which an extension handle may be threadedly attached, and a toothed blade portion having a semi-circular band extending outward from said handle. The openings between the teeth taper upwardly and terminate to a small near-full circle.

FIG. 1 is a rear perspective view from above of the garden weeder of the present design.

FIG. 2 is a front perspective view from above of the garden weeder of the present design.

FIG. 3 is a right side elevation view of the garden weeder of the present design.

FIG. 4 is a top plan view of the garden weeder of the present design.

FIG. 5 is a rear elevation view of the garden weeder of the present design; and,

FIG. 6 is a front elevation view of the garden weeder of the present design.
